UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

PIPE-HANGER.

1,106,078.

Specification of Letters Patent.

Patented Aug. 4, 1914.

Application filed June 28, 1913. Serial No. 776,417.

To all whom it may concern:

Be it known that I, HJALMAR G. CARLSON, a citizen of the United States, residing at Worcester, in the county of Worcester and State of Massachusetts, have invented a new and useful Pipe-Hanger, of which the following is a specification.

This invention relates to the construction of hangers for pipes and the principal objects thereof are to provide a simple and inexpensive kind of hanger for this purpose which can be pressed or rolled out of sheet metal in multiple sections so that any desired number can be cut off the blank and mounted in position without assembling any parts or performing any operations upon them, for the purpose of hanging any desired number of pipes. The invention involves a construction for this purpose consisting of a single part aside from the bolts by which it is hung.

Further objects and advantages of the invention will appear hereinafter.

Reference is to be had to the accompanying drawings in which—

Figure 1 is a side elevation of a preferred embodiment of this invention; Fig. 2 is a plan thereof; and Fig. 3 is an end elevation.

In the form in which the invention is shown, a pipe hanger is made in accordance therewith, consisting of a single piece of sheet metal rolled or pressed into the form in which a plurality of sections are connected and can be separated at any desired point.

Referring to the drawings each section consists of a single piece of sheet metal 10 having a pair of horizontal slits 11. The sheet metal between said slits is bent from the plane of the portion 10 in one direction to form a half 12 of a cylindrical passage. The metal above the upper slit and below the lower one is bent outwardly in the opposite direction to form two other portions 13 of the same passage. The bending of these parts is accomplished in such a way that each one is semi-cylindrical and the three members 13, 12 and 13 together constitute the cylindrical passage for a fastening and securing bolt 14. The head of this bolt when in position for holding the hanger receives the weight of the hanger and the pipes carried thereby. In order that a firm support may be given, the sheet metal at the

bottom is bent over to form a flange 15 to rest on the bolt head. This flange as well as the main body 10 of the hanger is provided with a vertical notch 16 and 17 respectively along which any two sections of the hanger can be separated from each other. It is understood, of course, that each section of the hanger is provided with a quadricircular notch 18 on opposite sides thereof and that two of these come together as indicated in Fig. 1 to constitute the support for the pipe. It will be seen, therefore, that an extremely simple arrangement is provided in which the hanger itself is made of a single sheet of metal, thus eliminating the necessity of fastening any two parts together, that there is no danger of any fastened parts becoming separated and no possibility of the hanger being wrenched loose from the bolts which support it. As long as the bolts hold, the hanger must also hold. In this way a very strong and durable construction is secured, manufactured in a very simple way and extremely inexpensively.

Although I have illustrated and described only a single embodiment of the invention, I am aware of the fact that many modifications can be made therein by any person skilled in the art without departing from the scope of the invention as expressed in the claims, therefore, I do not wish to be limited to all details of construction herein shown and described, but

What I do claim is:

1. As an article of manufacture a pipe hanger consisting of a single piece of sheet metal made in sections separable along vertical lines, and having a plurality of semi-cylindrical projections arranged on the opposite sides thereof and integral therewith, which, together, constitute a cylindrical passage for the reception of a supporting bolt. 95
2. As an article of manufacture, a pipe hanger comprising a piece of sheet metal having semi-cylindrical notches at the top for receiving the pipes to be supported and having two longitudinal slits between said notches, the sheet metal being bent alternately in reverse directions above and below each slit into opposite semi-cylindrical forms so as to constitute together a cylindrical passage for a vertical supporting bolt. 100
3. As an article of manufacture, a pipe

hanger having notches at the top for receiving the pipes to be supported and having a slit between said notches, the metal being bent in reverse directions above and below said slit so as to constitute together a passage for a vertical supporting bolt.

In testimony whereof I have hereunto set

my hand, in the presence of two subscribing witnesses.

HJALMAR G. CARLSON.
